UNITED STATES PATENT OFFICE.

HERMAN GILLIAN, OF COLUMBUS, OHIO.

GLOVE.

Application filed May 3, 1926. Serial No. 106,263.

This invention relates to gloves having wear facing and lining.

This invention has utility when incorporated in gloves having leather fingers and thumbs with fabric lining more especially as involving simplicity in stitching with resultant economies therefrom.

Referring to the drawings:

Fig. 1 is a front view of an embodiment 10 of the invention in a gauntlet type of work glove;

Fig. 2 is a side elevation of the glove of Fig. 1;

Fig. 3 is a back view of the glove of 15 Fig. 1;

Fig. 4 is a view of the blank front for the glove; said blank being provided in duplicate for each glove, one being leather as the outer face, and the duplicate thereof being 20 cloth or fabric for the lining;

Fig. 5 is a view of the blank for the fabric back serving, as to the finger portions, for lining;

Fig. 6 is a view of the blank for the thumb 25 back as of leather;

Fig. 7 is a view of the first finger wear facing back, as of leather;

Fig. 8 is a view of the second finger wear 30 facing back, as of leather;

Fig. 9 is a view of the third finger wear facing back, as of leather; and

Fig. 10 is a view of the little finger wear 35 facing back, as of leather.

Wear facing finger backs 1, 2, are assembled at portions 3, 4, by stitching 5. The blank 2 is assembled with blank 6 as to portions 7, 8, by stitching 9. The blank 6 is assembled with blank 10 at portions 11, 12, by stitching 13. There is thus provided a 40 unit of the finger back facings say of wear material or leather. This unit is then provided in the line of the finger bases 14, 15, 16, 17, with continuous overcast stitching 18. This wear facing back for the fingers is now 45 a completely assembled unit. This unit is then connected in the region of the overcast 18, by stitching 19 with finger back blank 20.

Glove front wear facing blank 21 is then placed in position over similar form fabric 50 lining 22. This front assembly is then assembled with the finger back facings and glove back 20 by stitching 23 extending up the side of the index finger and continuous over and about the several fingers to the base of the little finger. In this assembly 55 of the glove which is done with the parts

wrong side out, the stitching extending toward the wrist from the finger back facing unit, assembled the front lining 22 of fabric as well as the front facing 21 with the glove 60 back 20. However, in the continuation of this stitching along the finger sides, there is assembly only of the front wear facing with the finger back wear facing.

The tips of the fingers of the front lining 65 22 are assembled with the tips of the fingers of the back 20 at finger tip portions 24. Accordingly, the fabric lining of the front and back portions for the fingers is loose along the finger sides, and is held only terminally 70 by the seam 23 at the portions 24, in which position the seam 23 in this assembly is through four thicknesses of material.

In this glove, there is no occasion as herein disclosed, for any blind seam operation. 75 This is a material factor of economy in glove assembly. As a result of this mode of stitching, the output of the machine may be doubled for a given time. The fabric structure of the glove that is exposed is only the 80 back 20. The fabric portion 22 which is protected by the wear facing 21, may be of a much cheaper material, and in fact without detracting from the life of the glove and its ultimate or total wearing qualities, there 85 may be a saving of 12¢ per dozen in the use of say canton flannel instead of canvas as the fabric 22.

While this disclosure of the glove is referred to in the matter of woven fabric, the 90 analogous saving may be had in the knitted fabric or so-called jersey type of gloves. Accordingly, under the disclosure herein, the stitching assembly with the lining assembly in the character of gloves which might otherwise require a retail price of 75¢ per pair, with an adequate margin of profit under the disclosure herein, may be retailed for 50¢ per pair. Besides the increased output per machine in reducing the overhead, there is 95 an economy in the sewing cost as to labor amounting to 25¢ per dozen herein over other gloves which might be constructed in a competing field with the glove herein disclosed.

The finger backs, while assembled as a unit by the stitching herein disclosed, inasmuch 105 as these are of separate elements, are of forms which may be cut from culs from the glove fronts, and accordingly, this cost of producing the finger backs is, as to material, insignificant.

What is claimed and it is desired to secure by United States Letters Patent is:—

A glove having a one-piece wear facing front having integral palm and finger portions, a plurality of finger back wear facings terminating from the finger tips in the region of the crotches for the fingers, a one-piece lining front having integral palm and

finger portions, and a one-piece lining back having integral hand back and finger portions, a plurality of the finger back wear facings being stitched together to form a unit, said linings being stitched together at the tips of the fingers only. 10

In witness whereof I affix my signature.
HERMAN GILLIAN.
